UNITED STATES PATENT OFFICE.

OLIVER L. GARDNER, OF BROOKLYN, NEW YORK, ASSIGNOR OF ONE-HALF
TO ALFRED VAN DERWERKEN, OF SAME PLACE.

INTERIOR WALL FINISH.

SPECIFICATION forming part of Letters Patent No. 361,686, dated April 26, 1887.

Application filed July 22, 1886. Serial No. 208,777. (No model.)

To all whom it may concern:

Be it known that I, OLIVER L. GARDNER, a citizen of the United States, residing at Brooklyn, in the county of Kings and State of New York, have invented certain new and useful Improvements in Interior Wall Finish, of which the following is a specification, reference being had therein to the accompanying drawings.

15 This invention relates to the ornamentation or construction of walls, ceilings, &c.; and the novelty consists in the construction, arrangement, and adaptation of parts, as will be more fully hereinafter set forth, and specifically 15 pointed out in the claim.

The material used in carrying out the invention is known as "straw lumber," and comprises the article covered by Reissue Patent No. 10,387, of 1883, which patent I with others own 20 and control. It consists of a board or sheet of homogeneous material formed of several sheets of paper cemented and united by heat and pressure. With suitable sheets of this article I propose to form the walls and ceilings 25 of buildings, halls, and dwellings, or to decorate walls already formed in such places. The lumber may be kept in stock and in colors to imitate oak, cherry, walnut, maple, mahogany, &c. I design to render it possible at 30 short notice to finish a room in either of those or of other colors to suit different tastes.

By the employment of my invention a dining-room may in a short time be finished in cherry or other desired wood imitation. The 35 material will not shrink, does not need seasoning, and is without moisture; hence, when it is once in position, it is ready for immediate use.

I finish my walls in panels. Out of a proper 40 base-plate I cut a form smaller than the base-panel. Out of the base-panel I cut a section smaller than the cap-panel. I apply the base panel or band to the base-plate and the cap-panel to the base-panel in any suitable and 45 approved manner.

The piece cut out of the base-plate will serve as the cap-panel, and the piece cut out of the base-panel will serve with a separate and smaller series.

50 In the drawings, Figure 1 represents a vertical section taken through a wall partially

covered with panels constructed in accordance with my invention. Figs. 2 and 3 represent elevations of wall-sections finished with panels embodying my improvement. Fig. 4 represents an enlarged detail view of a series of panels formed upon a base common to all, and secured directly to the studs or joists of a wall or ceiling. Fig. 5 is a transverse sectional view taken on the line $x-x$ of Fig. 4. Fig. 6 represents a detail perspective view of a portion of a panel constructed in accordance with my invention.

Referring to the drawings, in which similar letters of reference denote similar parts, A 65 designates the base upon which the panels proper are secured, said base consisting of a series of sheets of paper cemented together to form a sheet or board of the required thickness.

a' designates cut-away portions of the base, to the side edges of which, upon the outer surface of the base, is cemented a base-panel, a^2 , of the material of which the base is formed, and similarly cut away, as at a' .

a^3 designates the outer finishing member of the panel, and is cemented to the outer surface of the band a^2 .

The outer side edges of the parts a^2 a^3 may have any desired configuration of outline, or 80 said members may be of any desired thickness, as desired.

In Figs. 1, 2, and 3 I have shown the base A as secured upon the outer surface of the wall covered by lath and plaster, and have in 85 said figures further shown different numbers of finish—as, for instance, the cornice, frieze, and picture-rail at the top of the wall, as well as the chair-rail, base, and sub-base at its bottom, formed of material similar in construction 90 to that of which the panel A is formed.

The panel a^3 may be hand-painted, as indicated, and these panels may be so secured as to be removable, allowing occupying parties to take their handiwork with them from one 95 residence to another. The faces of the entire work may be frescoed, painted, grained, or varnished in every manner the same as natural wood, and a fresh coat of paint at any time will make it as good as new.

The effect of the solid relief produced by my panels is as sharp and as bold as the finest

hand-carving. The general ornamentation may be readily changed by new combinations of colors, bronzing, burnishing, and metallic imitations.

5 I am aware that it is not new to make pasteboard with various figures and designs in relief by forcing one face of the pasteboard in and the other face out. In another application filed by me on the 22d day of July, 1886, 10 Serial No. 208,778, I have claimed a homogeneous board composed of several sheets of paper treated with an adhesive substance, the whole united by heat and pressure, and having one or both of its faces impressed or em-

bossed with figures formed in the process of manufacture.

What I claim as new is—

A wall or ceiling decorated by the application directly to the studding or joists of straw-board lumber embossed on the exposed surface, substantially as and for the purpose set forth. 20

In testimony whereof I affix my signature in presence of two witnesses.

O. L. GARDNER.
